UNITED STATES PATENT OFFICE.

HENRY C. BUCK, OF SOMERVILLE, ASSIGNOR TO FRANCIS M. HOLMES, OF BOSTON, MASSACHUSETTS.

TELEPHONE-TRANSMITTER.

SPECIFICATION forming part of Letters Patent No. 293,561, dated February 12, 1884.

Application filed June 27, 1881. (No model.)

To all whom it may concern:

Be it known that I, HENRY C. BUCK, of Somerville, in the county of Middlesex and State of Massachusetts, have invented certain new and useful Improvements in Telephone-Transmitters, of which the following is a full, clear, concise, and exact description, reference being had to the accompanying drawings, of which—

- 10 Figure 1 is a rear elevation. Fig. 2 is a section on line $x\ x$, Fig. 1. Fig. 3 is a diagram for illustration.
- 15 My invention relates to improvements in telephone-transmitters or microphones, in which one electrode is caused to press upon the other by gravity; and it consists in mounting one electrode upon a stand or holder, which rests at its lower end upon a base and leans toward the other electrode, the electrode 20 mounted upon the stand resting against the other electrode and pressing against it with a force due to the weight of the holder, but varying with the inclination of the holder from a vertical line. The more nearly vertical the 25 holder—that is, the nearer its center of gravity to a vertical plane passing through the points of support of the holder—the less the pressure of the electrode carried by the holder upon the other electrode, and the farther the center 30 of gravity of the holder from this vertical plane the greater the pressure of the electrode carried by the holder upon the other electrode. This is clearly shown by the diagram, Fig. 3, where a represents the electrode carried by 35 the diaphragm, b the electrode carried by the holder, and D the base upon which the holder rests, the middle dotted line x representing the diaphragm at rest, and the two carried to dotted lines $y\ z$ representing the limit of vibration of the diaphragm—greatly exaggerated 40 for clearness. From this diagram it will be clear at a glance that when the electrode a is carried backward by the vibration of the diaphragm to the limit indicated by the line y the pressure of the electrode b on electrode a is at the maximum, and that the pressure of b on a decreases as the diaphragm moves from y to z , and increases as the diaphragm 45

moves from z to y . The practical effect of this is to cause the pressure of electrode b on 50 electrode a , and some pressure is essential between the two, to diminish as little as possible the amplitude of the vibrations of the diaphragm.

In the drawings, A is the diaphragm; a , the 55 electrode fast to the diaphragm; b , the other electrode fast to the stand B . This stand is composed of a wire, b' , a piece of metal, b'' , of sufficient weight to give it steadiness, and the points $b^a\ b^b$, which rest in the mercury-cups on 60 the base D .

The transmitter is shown in section in Fig. 2, and corresponding parts are designated by the same letters.

The wires $f\ f'$ are in electrical connection, 65 one with the diaphragm A and with the base D , as will be understood without further explanation, so that the circuit is made through wire f , diaphragm A , electrodes $a\ b$, stand B , base D , and wire f' .

I am aware of Patents No. 225,790, dated 70 March 23, 1880, and No. 234,744, dated November 23, 1880, to E. Berliner, in both of which one electrode is suspended like a pendulum from a point above the other electrode 75 and kept out of a vertical position by contact with the lower electrode. I am also aware of United States Patent No. 237,633, dated February 8, 1881, to E. A. Schoettel, in which the diaphragm is not in the circuit. One end of 80 an inclined arm leans against it and transmits its vibrations to another arm connected to the first. In my transmitter or microphone the diaphragm forms part of the circuit, and one of the electrodes is attached to a weighted 85 holder, that rests on a base and is inclined out of the perpendicular and supported by the electrode on the diaphragm, so that when the diaphragm vibrates toward the holder it is brought nearer to the perpendicular and its 90 pressure decreases, and when it vibrates the other way the pressure increases and assists the vibrations, while in the pendulous position the opposite effects take place. I therefore disclaim all that is shown in these 95 patents.

What I claim as my invention is—

In a telephone-transmitter, the combination of an electrode, *b*, mounted on a stand, *B*, constructed substantially as described, a base, *D*, which supports the stand *B*, and the wire *f'*, electrically connected with base *D*, stand *B*, and electrode *b*, with the diaphragm

A, provided with an electrode, *a*, and wire *f*, substantially as and for the purposes set forth.

H. C. BUCK.
